US0D1047547S

(12) United States Design Patent (10) Patent No.: US D1,047,547 S
(45) Date of Patent: * Oct. 22, 2024

(54) OUTDOOR TABLE

(71) Applicant: Nanjing Haoyujie Electronic Technology Co., Ltd., Jiangsu (CN)

(72) Inventor: Meidi Chen, Jiangsu (CN)

(73) Assignee: Nanjing Haoyujie Electronic Technology Co., Ltd., Nanjing (CN)

() Term: 15 Years

(21) Appl. No.: 29/857,307

(22) Filed: Oct. 20, 2022

(51) LOC (14) Cl. 06-03

(52) U.S. Cl.

USPC D6/707.19; D6/691.1

(58) Field of Classification Search

USPC D6/329, 641, 656, 656.1, 656.13, 656.14, D6/656.18, 685, 687, 689, 690, 691, D6/691.1, 691.2, 691.3, 691.5, 691.6, D6/691.7, 691.8, 691.9, 707, 707.18, D6/707.19

CPC A47B 37/04; A47B 1/08; A47B 13/003; A47B 7/00

(57) CLAIM

The ornamental design for an outdoor table, as shown and described.

DESCRIPTION

FIG. 1 is a perspective view of an outdoor table showing my new design.

FIG. 2 is a front view of an outdoor table.

FIG. 3 is a rear view of an outdoor table.

FIG. 4 is a left side view of an outdoor table.

FIG. 5 is a right side view of an outdoor table.

FIG. 6 is a top view of an outdoor table; and,

FIG. 7 is a bottom view of an outdoor table.

The broken lines in the drawings depict portions of the outdoor table that form no part of the claimed design.

1 Claim, 7 Drawing Sheets
